UNITED STATES PATENT OFFICE

CLIFFORD A. CUTLER, OF BUFFALO, NEW YORK

DESIGN FOR A DESK

Application filed March 7, 1932. Serial No. 43,112. Term of patent 7 years.

To all whom it may concern:

Be it known that I, CLIFFORD A. CUTLER, a citizen of the United States of America, residing at the city of Buffalo, county of Erie, and State of New York, have invented a new, original, and ornamental Design for Desks, of which the following is a specification, reference being had to the accompanying drawing, forming a part thereof.

The figure of the drawing is a perspective view showing the front and one of the sides of the desk illustrating my new design.

I claim:

The ornamental design for a desk as shown. In testimony whereof, I have hereunto signed my name.

CLIFFORD A. CUTLER.
